TERMINAL OR CLAMP

Albert D. Goldman, Baltimore, Md.

Application September 21, 1928, Serial No. 307,416

1 Claim. (Cl. 173—259)

This invention relates to improvements in terminals or clamps now commonly used with battery terminals or other objects.

An object of the invention is to provide a positive means of removal of said terminal or clamp from a battery post or any member, removal from which has been made difficult due to corrosion, rust or other chemical action.

A further object of my invention is the provision of a terminal or clamp simple in operation and economical in manufacture as well as positive in action.

Other objects of the invention will become apparent as the description proceeds, when read in connection with the accompanying drawing.

The battery terminal or clamp now in use is secured to a battery post or other object to which it is attached by means of the customary bolt and nut fastening means. I have found from actual experience that such fastening means is rendered ineffective and that release thereof made extremely difficult because of the film formed between the bolt and the nut and between the post and terminals when corrosion occurs. This corrosion is brought about by the fumes or the acid escaping from the battery and covering the terminals and other parts causing the above described difficulties. This corrosive film may be in the form of rust when the clamp is used on an object which is exposed to the elements. With this form of fastening means it nearly always becomes necessary to use special tools to break the film and remove the clamp or terminal.

The device of my invention obviates the difficulties above pointed out in that it is not necessary to employ any tools other than a wrench in the removal of the clamp or terminal and to this extent presents a decided improvement over the prior art.

40 In the drawing:

Fig. 1 shows a plan view of my device.

Fig. 2 is a plan view of my device with the bolt removed.

Fig. 3 is a detail of the bolt.

45 Fig. 4 is a detail of the abutment collar.

Fig. 5 shows another form of my device.

Fig. 6 shows this form with the bolt removed.

Fig. 7 is a section of a part thereof.

Fig. 8 shows a third form of my device and

50 Fig. 9 shows a detail of the bolt used with this form.

Figures 1 to 3, inclusive, illustrate the preferred form of my invention. The body of my terminal or clamp is designated 10 and is provided with 55 projections 12 and 13. The projection 12 has an

opening 14 therein, said opening being threaded. Aligned with this opening and positioned in projection 13 is an opening 15. These openings are adapted to receive bolt 16 threaded from one end thereof to a recess 17 extending circumferentially of the bolt. A head 18 is formed on the other end of the bolt. An abutment collar 19 is provided which is adapted to seat in the recess 17.

The form of my device shown in Figs. 5, 6, and 7 is the same as that shown in Figs. 1, 2, and 3, 60 with the exception that a tapered groove 20 is provided in the body portion 10. This groove positioned in the projection 13 is placed at the inner end of the opening 15.

The third form of my device differs from the 70 form shown in Figs. 1, 2, and 3 in that a hole 21 is formed thru the bolt in place of the circumferential groove 17. Also a pin 22 is employed instead of the collar 19 said pin having a driving fit in the hole 21.

75 The operation of my device is as follows:

Assuming that my device is positioned on a battery, for example, with the body tightly embracing a post on said battery and it is desired to remove the device it is only necessary to turn 80 the bolt by means of any suitable tool in a direction to remove said bolt. The latter will be withdrawn from the openings referred to until the collar 19 abuts the inner face of the projection 13. Further withdrawal of said bolt will then 85 be prevented. However, since the opening 14 is threaded, further rotation of the bolt will tend to force the projection 13. This movement is possible because of the inherent resiliency of the metal of which my device is formed. Such movement, breaks the film of corrosion deposited between the body of the clamp and binding post of the terminal.

When the tapered groove is provided in the projection 13, as shown in Figs. 6, 7, and 8 and 91 the bolt is rotated as indicated above, the split ring or collar 23 will be forced into said groove 20 the taper thereof tending to force the ends of said collar, said ends being originally spaced from each other similar to ring 19 in Fig. 4, closer 100 together. This insures against the possibility of the collar 23 being forced out of the recess 17. The tapered surfaces of the collar 23 and groove 20 coact to force the spaced ends of the collar 23 together and effect a spreading of the clamp 105 when the bolt 16 is turned counter-clockwise.

The operation of the form shown in Figs. 8 and 9 is the same as for the other forms of my device, the pin acting as the abutment member in the same manner as the collar operates. 110

It is to be understood that I am not limited to the forms of my invention these being merely illustrative and that numerous changes may be made without departing from the spirit of my invention.

I claim:

A clamp for storage battery posts including opposed integral jaw members having their ends normally spaced and formed with apertures, the 10 aperture in one of said members being tapered toward the inner face of the said jaw member, a clamping bolt loosely mounted in the aperture in the said last mentioned jaw member and threaded through the aperture in the other jaw

15

member, a head on the bolt engaging the outer face of said last mentioned jaws, said bolt having an annular groove therein near the inner face of the last named jaw member, a split ring member disposed in said groove and having an 80 inclined exterior surface coating with the tapered aperture in said last mentioned jaw member, said ring member being movable with said bolt for effecting sliding engagement between the tapered face of said jaw member and the inclined exterior surface of said ring member whereby said jaw members may be spread for removing the clamp from a storage battery post.
